UNITED STATES PATENT OFFICE.

HENRY C. KING, OF HARRISON, ARKANSAS.

DESIGN FOR A SLATE-FRAME.

SPECIFICATION forming part of Design No. 19,345, dated October 8, 1889.

Application filed February 26, 1889. Serial No. 301,260. Term of patent 14 years.

To all whom it may concern:

Be it known that I, HENRY C. KING, a citizen of the United States, residing at Harrison, in the county of Boone and State of Arkansas, have invented a new and original Design 5 for Slate-Frames, of which the following is a specification.

The invention relates to a design for slate-frames, which is fully described hereinafter 10 in connection with the drawing and claimed.

In the drawing the figure represents a plan view of a slate made in accordance with my design.

The essential feature of my design is a rectangular frame A, provided at its center with 15 the transverse cross-piece B, which connects the centers of the sides of the frame. The slate is arranged upon each side of the central transverse cross-piece.

Having thus described the invention, I claim—

The design for slate, consisting of the rectangular frame provided with centrally-arranged triangular recesses, the central transverse cross-piece having pointed or beveled 25 ends, and the slate arranged upon each side of the central cross-piece, substantially as described.

In testimony that I claim the foregoing as my own I have hereto affixed my signature in 30 presence of two witnesses.

HENRY C. KING.
